ARTICLE HOLDER FOR A PERFORATED SUPPORT BOARD

John F. Nelson, 1688 Locust St., Cook County, Ill.

Filed Jan. 3, 1963, Ser. No. 73,045

Term of patent 14 years

(Cl. D17—12)

FIG. 1 is a perspective view of an article holder for a perforated support board showing my new design;

FIG. 2 is a bottom plan view thereof;

FIG. 3 is a side elevational view taken from the bottom of FIG. 2;

FIG. 4 is a rear elevational view;

FIG. 5 is a top plan view thereof;

FIG. 6 is a front elevational view; and

FIG. 7 is a side elevational view from the bottom of

FIG. 6.

I claim:

The ornamental design for an article holder for a perforated support board, as shown.
